(57) **CLAIM**

The ornamental design for a fertilizer tank for an agricultural implement, substantially as shown and described.

DESCRIPTION

FIG. 1 is a front view of a fertilizer tank for an agricultural implement;

FIG. 2 is a rear view thereof;

FIG. 3 is a left side thereof;

FIG. 4 is a right side thereof;

FIG. 5 is a front perspective view thereof;

FIG. 6 is a left perspective view thereof;

FIG. 7 is a right perspective view thereof;

FIG. 8 is a left rear perspective view thereof;

FIG. 9 is a top view thereof; and,

FIG. 10 is a bottom view.

The broken lines depict portions of the fertilizer tank for an agricultural implement that form no part of the claimed design.
